Design for Cooking Range

Issued Jan. 5, 1875.

UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR COOKING-RANGE.

Specification forming part of Design No. 7,996, dated January 12, 1875; application filed December 30, 1874.
[Term of Patent 3½ years.]

To all whom it may concern:

Be it known that we, NICHOLAS S. VEDDER, of the city of Troy, in the county of Rensselaer and State of New York, and TOBIAS S. HEISTER, of the village of Lansingburg, in the said county of Rensselaer, New York, have jointly invented and produced a new and original ornamental Design for Cooking-Ranges, of which the following is a specification, reference being had to the accompanying cut, print, or engraving of a cooking-range having our said new design.

One part of this invention consists of the design for the compound impression ornament A on the inner oblong rectangular panel B of the oven-door, composed of the two side branches b b, each having the oblong, sinuate, acuminate leaves c, florets d, and tendrils e, the central stem f, with florets thereon, and the pendant g, all shaped, arranged, and connected together, so as to appear substantially as represented in the aforesaid cut.

Another part consists of the design for the oven-door H, composed of the compound impression ornament A in the smooth surface of the oblong rectangular panel B, the inner ornamented border, i, around the panel B, the smooth inclined surface j surrounding the border i, and the outer surrounding border, k, formed by the single folded fillet l, all shaped and arranged together so as to appear substantially as shown in the said print.

Another part consists of the design for the door M, composed of the compound depressed ornament n, formed by two side branches with tendrils, florets, and sinuate acuminate leaves, a central stem with florets, and a pendent ornament below in the plain rectangular panel o, and the series of rounded projecting ornamentations p along and around the inner edge of the border of the upper panel, o, and lower panel, q, and the whole shaped and arranged together substantially as represented in the aforesaid engraving.

Another part consists of the design for the end plate, R, composed of the central compound scroll-leaf and pointed-leaf ornament s on the oblong rectangular inner panel, t, the ornamental inner border, u, the outer panel, v, and the surrounding zigzag-folded fillet l', and outer bead, w, all shaped and arranged together as shown in the aforesaid print.

We do not herein claim the design for a border formed by the zigzag-folded fillet l or l'.

What we claim as our joint invention is—

1. The design for the compound impression panel ornament A, composed of the side branches, b b, with leaves c, florets d, and tendrils e, the central floret-stem, f, and the pendant g, all shaped and arranged together as shown and described.

2. The design for the oven-door H, composed of the compound impression ornament A in the oblong rectangular panel B, the inner ornamental border, i, the incline surface j, and the outer surrounding border, k, formed by the zigzag-folded fillet l, all shaped and disposed as described and shown.

3. The design for the door M, composed of the compound depressed ornament n, formed as described, panels o and q, and surrounding-border ornamentations p, all shaped and arranged as shown and specified.

4. The design for the end plate, R, composed of the central compound ornament, s, inner panel, t, inner border, u, outer panel, v, surrounding zigzag-folded fillet l', and outer bead, w, all shaped and disposed as shown and described.

In testimony whereof we hereunto subscribe our names this 24th day of December, 1874.

NICHOLAS S. VEDDER.
TOBIAS S. HEISTER.
